UNITED STATES PATENT OFFICE

ANDREW G. SPEEGLE, OF IOLA, KANSAS

FLOATING DECK

Application filed October 17, 1929. Serial No. 400,265.

My invention relates to tanks and more particularly to floating decks for oil tanks, the principal objects of the invention being to effectually seal liquid in a tank from atmosphere, to retain a seal in sealing engagement with the tank while the deck is moving vertically therein and to maintain the seal when portions of the sealing element are distorted due to movement thereof over irregularities in the wall of the tank.

A floating deck for an oil tank is ordinarily provided with a peripheral sealing element engaging the wall of the tank and adapted to slide over the tank wall as the deck moves vertically due to changes in the level of liquid in the tank.

Slight variations in the diameter of the tank and irregularities due to distortion of the tank wall, seams connecting vertically adjacent tank rings, and the like, in ordinary construction, cause portions of a sealing ring to be displaced and permit leakage.

A further and particular object of my invention therefore is to assure engagement of sealing means with the tank wall while the deck is passing irregularities in the wall.

In accomplishing these and other objects of the invention, I have provided improved details of structure, the preferred forms of which are illustrated in the accompanying drawing, wherein:

Fig. 1 is a perspective view of a portion of a tank and floating roof equipped with my improved seal.

Fig. 2 is an enlarged vertical section of an upper edge portion of the tank, deck and seal illustrating the lower member of the seal displaced by a seam in the tank wall.

Fig. 3 is an enlarged detail perspective view of a longitudinal section of connected edge portions of sealing members illustrating a flexible element connecting the members.

Referring in detail to the drawing:

1 designates a top ring of an oil tank wall, 2 an adjacent lower ring having an upper edge overlapping the upper ring and attached thereto by rivets 3.

Riding on the surface of liquid 4 in the tank is a floating deck or roof 5 of smaller diameter than the tank to provide a circum-

ferential space 6 between the roof and the tank wall. Arcuate plates 7 are fixed to angles 8 attached to the periphery of the deck and have ends connected to form a complete circle around the deck and comprise a peripheral rim extending upwardly from the deck. The rim is braced and reinforced by means including stiffening brackets 9 to assure rigidity.

Fixed to the upper edge portion of the deck rim is an annular sealing element including a plurality of sections 10, each comprising a plate formed of spring steel bent to provide a seating or mounting web 11 on its median line and form diverging upper and lower wings 12 and 13 inclined outwardly and respectively upwardly and downwardly from the deck rim.

The webs of the sections are aligned on a circle surrounding the rim edge and are securely attached to the upper edge of the deck rim by rivets 14. The edge is reinforced by angles 15 also secured to the rim and sections by the rivets.

Flanges 16 comprising back bent outer edge portions of the wings 12 and 13 extend respectively upwardly and downwardly from said wings and inwardly toward the axis of the deck to form beveled edges of the wings for guiding the sections over protuberances from the tank wall.

Adjacent sections 10 are spaced laterally to provide for horizontal expansion and contraction of the tank and distortion of the sections, and flexible pliable webs 17 preferably of fabric connect vertical or end edges of adjacent sections and are attached thereto by bolts 18. The flexible members extend integrally over the flanges 16 and are sealingly secured thereto by bolts 19.

The sections are constructed of spring steel sheets or plates and the horizontal edges of the wings, namely the angles forming the meeting edges of the wings and flanges 16, engage the tank wall on vertically spaced lines to seal the space between the deck and the tank wall. The sections are originally constructed to extend substantially further than said space so that when the deck and sealing element are installed and assembled

- in the tank, the wings will press against the wall.
16. In using the device the floating deck will rise and fall responsively to changes in the elevation of liquid in the tank. Both of the spaced edges of the sealing element will normally engage the tank wall to prevent communication between atmosphere and the space in the tank below the deck.
10. When the rim of the floating deck passes one of the horizontal seams, the first of the edges of the wings to encounter the seam will yield and slide over the same, being led thereover by the inclined face of the flange.
15. The opposite resilient sealing edge however, will still be in contact with the smooth portion of the wall and will prevent movement of gases past the deck rim.
20. Gas or air that enters the annular space around the deck rim between the annular sealing rings due to displacement of one ring, will be prevented by the outer ring from passing onwardly to atmosphere or to the tank as the case may be.
25. The pliable character of the connecting webs between sections permits flexing of the sections and at the same time renders the annuli comprising a complete series of sections imperforate to retain gases.
30. What I claim and desire to secure by Letters Patent is:
1. In a floating deck for tanks, peripheral sealing means for the deck comprising spring metal plate sections having upper and lower wings diverging outwardly toward the walls of the tank to sealingly contact therewith and prevent leakage around the periphery of the deck, said wings being arranged for independent movement relatively to each other, whereby one of the wings is sealingly engaged with the wall of the tank when the other is moving over an obstruction on the tank.
  45. 2. In a floating deck for tanks, peripheral sealing means for the deck comprising metal plate sections having intermediate portions fixed to the deck and forming outwardly diverging upper and lower wings for yieldingly engaging the walls of the tank and arranged for independent movement relatively to each other, whereby one of the wings is in engagement with the wall of the tank when the other is moving over a projection on the tank.
  50. 3. In a floating deck for tanks, peripheral sealing means for the deck comprising spring metal plate sections having upper and lower wings diverging outwardly towards the wall of the tank and terminating in angularly extending guide flanges forming line contact with the wall of the tank, said wings being arranged for independent movement relatively to each other, whereby one of the wings
  55. may remain in sealing engagement with the wall of the tank when the other is moving over a projection on the tank.
4. In a floating deck for tanks, peripheral sealing means for the deck comprising spring metal plate sections having upper and lower wings diverging outwardly toward the wall of the tank and terminating in angularly extending guide flanges forming line contacts with the wall of the tank, said wings being arranged for independent movement relatively to each other, whereby one of the wings is in engagement with the wall when the other is moving over a projection on the tank, and flexible webs connecting the upper wings of the sections to seal the joint between the sections. 70
5. In a floating deck for tanks, peripheral sealing means for the deck comprising spring metal plate sections having upper and lower wings diverging outwardly towards the wall of the tank and terminating in angularly extending guide flanges forming line contact with the wall of the tank, said wings being arranged for independent movement relatively to each other, whereby one of the wings may remain in sealing engagement with the wall of the tank when the other is moving over a projection on the tank, and flexible webs connecting the upper wings of the sections to seal the joint between the sections. 75
6. In a floating deck for tanks, peripheral sealing means for the deck comprising spring metal plate sections having upper and lower wings diverging outwardly toward the wall of the tank and terminating in angularly extending guide flanges forming line contact with the wall of the tank, said wings being arranged for independent movement relatively to each other, whereby one of the wings is in engagement with the wall when the other is moving over a projection on the tank, and flexible webs connecting the upper wings of the sections to seal the joint between the sections. 80
7. In a floating deck for tanks, peripheral sealing means for the deck comprising spring metal plate sections having upper and lower wings diverging outwardly towards the wall of the tank and terminating in angularly extending guide flanges forming line contact with the wall of the tank, said wings being arranged for independent movement relatively to each other, whereby one of the wings may remain in sealing engagement with the wall of the tank when the other is moving over a projection on the tank, and flexible webs connecting the upper wings of the sections to seal the joint between the sections. 85
8. In a floating deck for tanks, peripheral sealing means for the deck comprising spring metal plate sections having upper and lower wings diverging outwardly toward the wall of the tank and terminating in angularly extending guide flanges forming line contact with the wall of the tank, said wings being arranged for independent movement relatively to each other, whereby one of the wings is in engagement with the wall when the other is moving over a projection on the tank, and flexible webs connecting the upper wings of the sections to seal the joint between the sections. 90
9. In a floating deck for tanks, peripheral sealing means for the deck comprising spring metal plate sections having upper and lower wings diverging outwardly towards the wall of the tank and terminating in angularly extending guide flanges forming line contact with the wall of the tank, said wings being arranged for independent movement relatively to each other, whereby one of the wings may remain in sealing engagement with the wall of the tank when the other is moving over a projection on the tank, and flexible webs connecting the upper wings of the sections to seal the joint between the sections. 95
10. In testimony whereof I affix my signature.
- ANDREW G. SPEEGLE.
